UNITED STATES PATENT OFFICE.

JAMES THOMPSON SWARTZ, OF NEBRASKA CITY, NEBRASKA, ASSIGNOR TO
CHARLES A. VAN PELET, OF SAME PLACE.

WIRE-STAY-WEAVING DEVICE.

SPECIFICATION forming part of Letters Patent No. 660,668, dated October 30, 1900.

Application filed June 30, 1900. Serial No. 22,224. (No model.)

To all whom it may concern:

Be it known that I, JAMES THOMPSON SWARTZ, a citizen of the United States, residing at Nebraska City, in the county of Otoe and State of Nebraska, have invented a new and useful Fence-Weaving Device, of which the following is a specification.

This invention relates to a novel fence-weaving device, and contemplates the organization of a simple and inexpensive tool by the use of which wire stays may be stretched between and wound upon the longitudinal wires or stringers of a fence with facility and despatch.

One of the objects of the invention is to produce a simple device of this character by the manipulation of which the sections of the stay lying between each pair of stringers may be subjected to considerable tension and a closely-wound coil produced upon each stringer and which may be employed with equal facility for the weaving of straight, diagonal, or other forms of stays, whereby the construction of fences of various designs is made possible.

Further objects of the invention are to facilitate the initial attachment of the stay to the top stringer or fence-wire without necessity for the employment of a supplemental device and to construct the wire-supporting spindle in a manner to prevent the displacement of the wire during the manipulation of the tool.

To the accomplishment of the several objects enumerated and others which will hereinafter more fully appear the invention comprehends details of construction and arrangement hereinafter fully described, and comprehended within the scope of the appended claims.

In the accompanying drawings, Figure 1 is a perspective view of a section of wire fencing, showing the stringers connected by a stay woven with my device and also illustrating the weaving device in position to simultaneously form a pair of coils at the beginning of the operation of forming a stay. Fig. 2 is an end view of the tool on a somewhat-enlarged scale and showing somewhat more clearly the relation of the tool to the stringers and stay-wire in that position of the tool illustrated in Fig. 1. Fig. 3 is a view similar to Fig. 2,

showing the top loop of the stay completed and the tool advanced to the stringer next below and in the act of forming a coil thereon. Fig. 4 is a detail perspective view of the tool. 55 Fig. 5 is a view serving to illustrate the manner of manipulation of the tool to increase the tension on the stay during the formation of the coil.

Referring to the numerals of reference employed to designate corresponding parts and structural features in the several views, 1 indicates a fence-post, and 2, 3, 4, 5, and 6 indicate a series of horizontal wires or stringers connected to the post in any ordinary manner. 65

7 indicates a wire stay of the form produced by the manipulation of my tool and comprehending a stay-loop 8, formed by looping the stay-wire over the top stringer 2 and securing the extremity 9 of the wire and also the coincident intermediate portion of the wire to the stringer 3 by a double coil 10. From the double coil 10 the wire is advanced to or coiled upon each successive stringer until the stay is completed. I have described the construction of the stay with some particularity in order that the succeeding description of the construction and operation of the tool may be more clearly understood. 75

The stay-weaving tool comprehending the 80 subject-matter of my invention is composed of a metal shank 11, having a handle 12 located at one end of the shank and extending at right angles thereto. The end of the shank opposite the handle is provided with an open-ended slot 13, which constitutes an elongated socket for the reception of the stringers of the fence, so that when the device is applied to a stringer, as shown in Fig. 1 of the drawings, the handle 12 will lie normally substantially parallel with the stringer. Inasmuch as it is necessary and desirable during the manipulation of the tool to throw the handle out of its true parallel relation with the adjacent stringer, the slotted or bifurcated end 14 95 of the shank 11 is deflected or curved slightly out of the plane of the shank toward the side from which the handle 12 extends.

15 indicates the spindle of the tool, extending from the shank 11 substantially parallel 100 with the handle 12 and tapered toward its outer end 16, which is curved toward the han-

dle, as shown, to constitute a guard, preventing the accidental displacement of a coil 17 of stay-wire wound upon the spindle, as shown in Fig. 1, and designed to be paid out during 5 the formation of the stay. Intermediate of and preferably about midway between the spindle and the slot 13 the shank 11 is pierced by an eye or opening 18 for the reception of the extremity of the stay-wire, as will be de- 10 scribed, the axis of said eye being parallel with the spindle.

The weaving of a fence-stay is accomplished by the following manipulation of the tool: The coil 17 of stay-wire is first placed upon 15 the spindle 15, after which a short length of the wire is drawn from the spindle, and the bifurcated end 14 of the tool is slipped into engaging position with the stringer 3, which, as shown, is that stringer lying below the top 20 stringer of the fence. The short length of wire which has been unwound from the spindle is now passed in front of the stringer 3 and is passed behind and over the top stringer 25 to form the stay-loop 8, after which the extremity of the wire is passed through the eye 18 in the shank from the outside—that is to say, from the side opposite the spindle. The operator now grasps the handle and rotates the tool around the stringer 3 in the di- 30 rection of the arrow in the several figures. The effect of this manipulation is to cause the end of the wire and also that portion of the wire lying immediately opposite the stringer 3 to be wound upon said stringer in a double 35 coil until the wire end 9 has been consumed, and thereby released from the eye 18. The stay-loop 8 will now have been formed and coiled at both ends upon the stringer 3, from which the tool is now released and advanced 40 to the next lower stringer, a short length of the stay-wire being obviously uncoiled from the spindle to connect the stringers 3 and 4. The tool is then rotated, as before indicated, around the stringer 4 to form a short close 45 coil thereon, after which it is advanced to each succeeding stringer until the entire stay is woven upon the fence and severed from the coil of wire 17 upon the spindle unless said coil shall have contained only sufficient wire 50 for the formation of a single stay. Attention is called to the fact that great tension is obtained upon the stay-wire, because the device is fulcrumed upon the stringer precisely at that point where the stay-coil is formed; also, 55 that the tool having a single point of attachment to the stringer and having its engaged

end deflected away from the stay-wire may be raised by a slight twist of the device—that is to say, by throwing the outer end of the handle slightly nearer the stringer during the rotation of the tool—to augment the direct tension which the tool exerts upon the wire by urging the side of the shank against the coil as the latter is being formed in order to form a more compact retaining-coil upon each 60 stringer.

From the foregoing it will be observed that I have produced a stay-wire-weaving device of simple and inexpensive construction which may be quickly and conveniently manipulated 65 to form vertical, diagonal, or other stays upon wire fences; but while the present embodiment of the invention is believed at this time to be preferable I wish to be distinctly understood as reserving the right to effect such 70 structural modifications as may be comprehended within the scope of the protection 75 prayed.

What I claim is—

1. A wire-stay-weaving device comprising 80 a shank having a bifurcated end, and a handle extending at right angles to the shank from its opposite end, a spindle extending from the shank parallel with the handle, the bifurcated end of said shank being deflected 85 beyond the side of the shank from which the spindle and handle extend, and said shank being provided with an eye having its axis parallel with the spindle and located between said spindle and the bifurcated end of the 90 shank.

2. A wire-stay-weaving device comprising 95 a shank having a bifurcated end, and a handle extending at right angles to the shank from its opposite end, a spindle extending from the shank parallel with the handle and having its outer end deflected toward the handle to form a guard, the bifurcated end of said shank being deflected beyond the side of the shank from which the spindle and handle 100 extend, and said shank being provided with an eye having its axis parallel with the spindle and located between said spindle and the bifurcated end of the shank.

In testimony that I claim the foregoing as 105 my own I have hereto affixed my signature in the presence of two witnesses.

JAMES THOMPSON SWARTZ.
